GROSVENOR P. ROBINSON, OF SUMMIT, AND WILLIAM T. BLACKWELL, OF WESTFIELD, NEW JERSEY; SAID ROBINSON ASSIGNOR, BY MESNE ASSIGNMENTS, TO SAID WILLIAM T. BLACKWELL.

LIGHTING FIXTURE.

Application filed June 7, 1924. Serial No. 718,449.

Our present invention relates generally to electric light fixtures, and is particularly adapted for use upon the ceilings of kitchens, corridors and porches, in which fixtures it is desirable that lamps of 100 watts or over be employed, and lamps of such character are provided when the fixtures are installed.

It has been found in practice, that the efficiency of such fixtures is very commonly impaired by the substitution of lamps of less power, when the lamps originally provided become broken or burned out.

The object of our invention is to overcome this objection by providing a fixture that will not receive a lamp of less than 100 watt, thereby insuring uniform capacity of the fixture.

The details of construction and operation of our improved fixture are hereinafter particularly described.

In the accompanying drawing:

Figure 1 is a vertical central section of a lighting fixture embodying our invention.

Fig. 2 is an elevation of the stop member, detached, and

Fig. 3 is a bottom view of the same.

Similar reference characters denote like parts in all the views.

The body of the fixture comprises a canopy 10 adapted to be secured to the ceiling in any suitable manner, such as by screws or bolts passed upwardly through holes 11 in the annular horizontal flange 12 on the canopy.

Below said flange 12, the canopy is tapering and its bottom edge turned inwardly forming an annular horizontal flange 13. Depending from the bottom of the canopy 10 is a shell 14, its top being of the same diameter as that of the lower end of the canopy and provided with an inturned annular horizontal flange 15, which contacts with the flange 13, at the bottom of the canopy, these flanges being secured together by any suitable means. Below this connection with the canopy 10, the shell 14 is curved downwardly and outwardly for a predetermined distance from which point it extends vertically to its bottom, in which vertical portion there is provided spaced threaded bushings 16, for the reception of set screws 17 for supporting a globe or shade 18 in the customary manner.

The body of the fixture thus formed and having its outer surface coated with enamel, has the outward appearance of being made as a unit.

A porcelain receptacle 19, is connected within the body at the junction of its two members, the bottom of the receptacle being seated upon the flange 13 of the canopy 10, while the threaded metallic member 20 extends below the flange 15 on the shell 14 and upon which is screwed a porcelain ring 21, between which and the flange 15, is preferably provided a rubber washer 22. The receptacle is thus securely held in the desired position within the body of the fixture, and furthermore strengthens the connection of the canopy 10 with the globe supporting shell 14.

23 denotes a stop member, which prevents a lamp of less than 100 watt being connected with the receptacle 19. This member 23 is preferably formed from a flat piece of sheet metal, pressed into the form shown most clearly in Figs. 2 and 3. The circumference of the horizontal flange 24, at the top of the member 23, is slightly less than that of the circular vertical portion 25, of the bottom part of the shell 14, so that the said flange 24 fits snugly within the said vertical wall of the shell 14, and contacts with the shoulder formed at the upper inner end of said vertical part of said shell, at which point it is preferably permanently secured within the shell by solder, or other suitable means.

The body of the member 23 is tapered below the flange 24 and is of a predetermined depth, its bottom edge being preferably bent inwardly forming a flat horizontal flange 26, leaving a central opening 27. This opening 27 is of a size to permit the passage of the neck 28 of a lamp bulb 29 which contacts with the annular flange 27, when the plug 30 at the end of its neck 28, is screwed into the threaded metallic member 20, of the receptacle 19, the bottom of the member 23 being spaced below the lamp receptacle 19 at the precise distance to allow a lamp of 100 watts or over to be thus connected with the receptacle.

All lamps of less than 100 watt are provided with necks of less length than are lamps of 100 watt or over; it will thus be seen that if an effort is made to insert a

2
lamp of less than 100 watt, its bulb will at its bottom, a shell having an inwardly contact with the flange 26, before its neck turned annular flange at its top in contact reaches the threaded member 20 of the receptacle 19, rendering it impossible to connect such lamp with the receptacle. 25

The entire outer surface of the member 23 is preferably coated with white enamel so that owing to their relative positions, the light from the lamp striking this surface is reflected therefrom downwardly into the globe; this member therefore performs a very advantageous secondary function. 30

In lighting fixtures of the character to which this invention relates, it is very desirable that a certain and uniform lighting capacity be maintained, and it will readily be understood that by the employment of our invention such object is assuredly accomplished. 35

20 We claim as our invention:

In a lighting fixture comprising a canopy having an inwardly turned annular flange

at its top in contact with and corresponding with the flange on the canopy, a lamp receptacle seated upon the flange on the canopy and having a

threaded metallic member extending below said threaded member, a ring of non-conducting material screwed upon

light from the lamp striking this surface said threaded member, a lamp stop secured within the shell below said receptacle at a

predetermined distance therefrom and provided with an opening in alignment with

the neck of which passes through such opening and into connection with said receptacle,

connection where the neck of the lamp bulb is of a predetermined length. 40

Signed by us this 3rd day of June, 1924.

GROSVENOR P. ROBINSON.

WILLIAM T. BLACKWELL.
